CLAIM

The ornamental design for an adapter for installation of a turbocharger, as shown and described.

DESCRIPTION

FIG. 1 depicts a front and left side perspective view of an adapter for installation of a turbocharger showing my new design;

FIG. 2 depicts a front elevational view of the adapter for installation of a turbocharger based on FIG. 1;

FIG. 3 depicts a rear elevational view of the adapter for installation of a turbocharger based on FIG. 1 and the reverse view of FIG. 2;

FIG. 4 depicts a top plan view of the adapter for installation of a turbocharger based on FIG. 1;

FIG. 5 depicts a bottom plan view of the adapter for installation of a turbocharger based on FIG. 1 and the reverse view of FIG. 4;

FIG. 6 depicts a left elevational view of the adapter for installation of a turbocharger based on FIG. 1;

FIG. 7 depicts a right elevational view of the adapter for installation of a turbocharger based on FIG. 1 and the reverse view of FIG. 6; and,

FIG. 8 depicts a front perspective view of the adapter for installation of a turbocharger based on FIG. 1 with the adapter for installation of a turbocharger installed on a pedestal and with a turbocharger installed on the adapter for installation of a turbocharger.

(Continued)

The broken lines in FIG. 5 and FIG. 8 depict recesses, a pedestal, mounting hardware, and a turbocharger and form no part of the claimed design.
